FAN HOUSING

William R. Heath, Buffalo, N. Y., assignor to
 Buffalo Forge Company, Buffalo, N. Y., a corporation of New York

Application June 12, 1948, Serial No. 32,555

6 Claims. (Cl. 230—128)

1

My invention relates in general to fan housings, and in particular to scroll-shaped housing for use in blower fans or pumps of the centrifugal type.

As is well known to those skilled in the art, the scroll-shaped casing of a centrifugal blower fan not only acts as a collector to gather the fluid leaving the impeller of the fan and to conduct it to a central point where it may be easily fed into a conventional pipe or duct, but also serves to act as a diffuser to convert the kinetic energy in the fluid, in the form of high velocity leaving the periphery of the impeller, into more useful potential energy in the form of pressure at the discharge end of the housing. In order that a blower fan have good efficiency, it is necessary that the scroll-shaped housing of the fan be designed to pick up the fluid at approximately the velocity at which it is leaving the periphery of the impeller and to slow it down gradually to a more useful terminal velocity. This result may be accomplished by extending the discharge duct a considerable distance beyond the main body of the casing. Another way of achieving this result, in cases where space and cost are to be considered, is to provide the housing with an outwardly flaring discharge duct which is connected to an outlet duct larger in size than the regular outlet of the casing. A similar result is accomplished by attaching the outlet of the housing to a duct larger in size than the outlet discharge opening.

When it is attempted to accomplish the above results by either an extended or an enlarged outlet duct, some of the kinetic energy is converted into potential energy in the duct, but at reduced efficiency. When, however, the flaring outlet is used, there is little or no conversion of energy and the efficiency of the fan is correspondingly reduced. A further disadvantage of the use of the flaring discharge duct is that the fluid is forced to the outer surface of the duct by centrifugal force, and this condition is aggravated when the fan is throttled below a definite minimum value of delivery relative to the speed of the fan.

It is well known that the velocity of the fluid leaving the impeller of a centrifugal blower or pump varies with the amount of resistance in the system supplied by the pump or fan so that the scroll-shaped housing is only theoretically correct for a narrow range of fluid delivery relative to the speed of rotation of the blower wheel. When the fan is throttled below this theoretically correct point, the scroll is larger than that required for efficient operation. With certain impeller

2

designs, it frequently happens that appreciable energy conversion is obtained above certain fluid deliveries when the fluid "fills" the outlet, but little conversion is obtained with slightly less delivery when the fluid does not "fill" the outlet. The point where the fluid flow changes is not clearly defined but varies with slight changes in flow conditions so that the entire output of the fan becomes unstable.

10 Numerous attempts have been made heretofore to overcome the above disadvantages and various expedients have been employed, such as deflectors located in the outlet of the casing and positioned as to direct the air toward the center of the outlet. 15 When such deflectors are fixed in position, the capacity of the fan is thereby reduced; and, if it is attempted to overcome this disadvantage by making the deflectors adjustable, then the deflectors must be adjusted for each operating 20 condition to which the fan is subjected in order to bring about efficiency of operation. Moreover, other disadvantages of the use of such deflectors are that undesirable noises are created and the deflectors must be detached and removed from 25 the housing when the wheel of the fan is to be removed through the discharge opening thereof.

In carrying out my invention, it is a principal object to produce a blower fan having a housing so designed that the disadvantages above pointed out may be overcome, and one in which the maximum amount of kinetic energy in the fluid may be converted into potential energy at the outlet or discharge opening of the fan.

Another object is to provide a blower housing so formed that high fan efficiencies may be achieved, while at the same time bringing about a reduction in the cost of manufacture of the fan and the space occupied thereby.

A further object is to provide a fan housing of scroll-shape which will embody all of the advantages of my invention, and at the same time have a discharge opening so proportioned that the fan wheel of the blower may be removed therethrough.

45 A further object is to provide a housing for a blower fan having an outlet passageway so formed as to direct the moving fluid toward the center of the opening.

Moreover, by means of my invention, a stable 50 operation of my fan is assured when operating under varying delivery conditions and where at times the blower is throttled down with a consequent minimum value of delivery relative to wheel speed.

The above objects and advantages have been

accomplished by the device shown in the accompanying drawings, of which:

Fig. 1 is a front elevational view of a blower fan embodying my invention; and

Fig. 2 is a side elevation of the fan with a portion of the casing broken away.

My blower fan comprises a housing 10 of usual scroll-shape having side walls 11 and 12 connected together by the scroll-shaped outer wall 13.

The housing is supported in operable position by any suitable means, and for convenience of illustration I have shown two pedestals 14, one secured to each of the side walls 11 and 12 by any suitable means. Each pedestal is preferably formed with a base flange 15 and with an upper flange 16. The flanges 16 of the pedestals support the bearings 20 within which the wheel shaft 21 of the device is rotatably mounted. The shaft 21 carries the wheel 22 of the blower fan. This wheel may be any one of a number of different types and comprising in general, a plurality of blades 23 at each side of which is provided a shroud ring 24. The blades 23 are preferably secured at their inner ends to a wheel hub 25 which in turn is mounted upon the shaft 21.

In carrying out my invention, I have shown it as applied to a double inlet fan. Each of the walls 11 and 12 of the housing is therefore provided with an inlet eye 30 opposite each end of the fan wheel 22. As is customary, each of these eyes is flared inwardly and is of a diameter preferably slightly less than the diameter of the opening of the adjacent shroud ring 24 of the wheel. The housing is also formed with the usual discharge collar 31 which forms the discharge opening 32 of the fan. The housing is provided with a short neck rectangular in cross section which is located between a short discharge collar and the inner and outer ends of the scroll-shaped outer wall, and serves to join these casting parts. The top part of the neck is formed with an inwardly-bowed portion 33 of continuous curvilinear contour which is connected to the outer end of the outer wall 13 in tangential manner forming a streamlined surface which avoids the formation of eddies in the discharge collar 31 and the discharge duct (not shown) to which the collar is connected. This inwardly-bowed portion serves to direct the air toward the center of the opening and immediately thereafter to expand it into the collar. The bottom wall of the neck is also provided at the housing cutoff with an inwardly-bowed portion 34 also of continuous curvilinear contour. These oppositely arranged inwardly-bowed portions which are substantially flat in lateral cross section serve to streamline the discharge opening of the housing, and to project the air stream from opposite sides of the opening in jet-like manner toward the center of the housing outlet and to immediately expand it outwardly in substantially uniform manner in the short collar and thereby to substantially fill the collar upon entrance of the air stream therein, thus preventing the formation of eddies, thereby bringing about smooth and efficient conversion of the kinetic energy of the moving fluid into potential energy.

From the foregoing it will be obvious that as the fluid approaches the discharge opening 32, the nozzleing effect of the inwardly-bowed curved wall portions causes a centering action upon the stream, as just above described, and permits efficient conversion from kinetic to potential energy within the housing 10 of the fan without

the necessity of an extended outlet duct or an outwardly flaring nozzle. By streamlining the passageway leading to the discharge opening 32, the stream is thereby nozzleed down and permitted to expand smoothly in two directions, thus enabling even small quantities of air to fill the discharge collar. This centering action is advantageous under substantially all conditions of fan performance, but is particularly advantageous when the fan is operating at a minimum value of delivery relative to the speed of rotation of the fan wheel. My invention eliminates substantially all instability occurring in blower fans resulting from the use of straight-sided discharge ducts especially those operating under the above mentioned conditions.

While I have shown my invention as applied to a blower fan having two inlet eyes, it is obvious that similar advantages may be achieved when my invention is used in connection with fans having but a single eye.

What is claimed is:

1. A housing for a blower device having a scroll-shaped outer wall, substantially flat side walls joining the outer wall, a fan wheel rotatably mounted within the housing, a discharge collar provided at the outlet end of the housing for attachment to a discharge duct, an inwardly-bowed curved portion at the outer end of the outer end of the outer wall, the curved portion forming a part of a constricted neck located between the collar and the outer wall, the neck being relatively short with respect to the length of the outer wall, the inwardly-bowed wall portion curving inwardly in tangential manner from the scroll-shaped wall and thence outwardly to the collar in substantially one continuous smooth curved contour to direct the air stream initially toward the center of the neck and thereafter to expand it outwardly into the collar by reason of the curved streamline contour of the neck to substantially fill the collar immediately upon entrance of the air stream therein, thus preventing the formation of eddy currents.

2. The combination according to claim 1 wherein the neck and the collar throughout their length are of greater dimension in cross-section than the diameter of the fan wheel to enable the mounting and dismounting of the wheel therethrough.

3. A housing for a blower device having a scroll-shaped outer wall, substantially flat side walls joining the outer wall, a fan wheel rotatably mounted within the housing, a discharge collar provided at the outlet end of the housing for attachment to a discharge duct, an inwardly-bowed curved portion at the outer end of the outer wall, an inwardly-bowed curved portion at the inner end of the outer wall, forming the housing cutoff, the inwardly-bowed portions being oppositely arranged and forming a restricted neck joining the scroll-shaped outer wall to the collar, said neck being relatively short with respect to the length of the outer wall, the inwardly-bowed portions curving inwardly in tangential manner from the scroll-shaped wall and thence outwardly to the collar each in substantially one continuous smooth curved contour to direct the air stream initially toward the center of the neck and thereafter to expand it outwardly into the collar by reason of the curved streamline contour of the neck to substantially fill the collar immediately upon the entrance of said air stream therein, thus preventing the formation of eddy currents.

4. The combination according to claim 3, wherein the cutoff is so located that the center line of the fan wheel which lies in a plane substantially parallel to the axis of the outlet is disposed between the said cutoff and the outer end of the wall oppositely thereto, and the distance between the oppositely arranged inwardly-bowed portions being greater than the diameter of the fan wheel to enable the mounting and dismounting of the wheel therebetween.

5. A housing for a blower device having a scroll-shaped outer wall, substantially flat side walls joining the outer wall, a fan wheel rotatably mounted within the housing, a discharge collar provided at the outlet end of the housing for attachment to a discharge duct, an inwardly-bowed curved portion at the outer end of the outer wall, the length of the collar being less than the length of the inwardly-bowed portion, the curved portion forming a part of a constricted neck located between the collar and the outer wall, the neck being relatively short with respect to the length of the outer wall, the inwardly-bowed wall portion curving inwardly in tangential manner from the scroll-shaped wall and thence outwardly to the collar in substantially one continuous smooth curved contour to direct the air stream initially toward the center of the neck and thereafter to expand it outwardly into the collar by reason of the curved streamline contour of the neck to substantially fill the collar immediately upon entrance of the air stream therein, thus preventing the formation of eddy currents.

6. A housing for a blower device having a scroll-shaped outer wall, substantially flat side walls joining the outer wall, a fan wheel rotat-

ably mounted within the housing, a discharge collar provided at the outlet end of the housing for attachment to a discharge duct, an inwardly-bowed curved portion at the outer end of the outer wall, the length of the collar being less than the length of said inwardly-bowed portion, an inwardly-bowed curved portion at the inner end of the outer wall, forming the housing cutoff, the inwardly-bowed portions being oppositely arranged and forming a restricted neck joining the scroll-shaped outer wall to the collar, said neck being relatively short with respect to length of the outer wall, the inwardly-bowed portions curving inwardly in tangential manner from the scroll-shaped wall and thence outwardly to the collar each in substantially one continuous smooth curved contour to direct the air stream initially toward the center of the neck and thereafter to expand it outwardly into the collar by reason of the curved streamline contour of the neck to substantially fill the collar immediately upon entrance of said air stream, thus preventing the formation of eddy currents.
